(57) **CLAIM**

The ornamental design for a sock with folded hem, as shown and described.

DESCRIPTION

FIG. 1 is an isometric view of a sock with folded hem showing my new design;

FIG. 2 is a top plan view thereof;

FIG. 3 is a front elevation view thereof, the back elevation view being a mirror image thereof;

FIG. 4 is a left side view thereof;

FIG. 5 is a right side view thereof; and,

FIG. 6 is a bottom plan view thereof.

The broken lines depict portions that form no part of the claimed design.
